UNITED STATES PATENT OFFICE.

JULES L. HENRY, OF YSLETA, TEXAS.

LAND-LEVELING MACHINE.

Application filed August 27, 1926. Serial No. 131,957.

This invention appertains generally to new and useful improvements in land leveling machines and relates particularly to such an improved machine primarily designed 5 for the leveling of irrigating tables.

In irrigating farming, a table is a strip of land approximately thirty to forty feet wide and of variable length, this strip of land being bordered on its opposite sides and divided from the adjacent tables by means of 10 ridges so that water may be turned in at one end of the table and allowed to run thereover until it reaches the other end after which the water is shut off and turned into 15 the next table so as to irrigate the same.

In table leveling, it is not important whether there be very much or little or in fact, any difference between the level of one table and that of any other table but it is 20 extremely important that there be just a slight difference in the level of a table between the ends thereof and the table should slope down from the irrigating ditch towards the other or opposite end thereof.

25 Not only must the surface of the table be a perfect plane, without hollows or humps but the dirt for leveling the same must all come from the higher end of the table and be smeared along towards the lower end 30 thereof.

It is, therefore, the purpose and primary object of the present invention to provide such an improved land leveling machine of the above character whereby the proper and 35 even leveling of an irrigating table can be readily and efficiently achieved.

Another object of the present invention is to provide such an improved land leveling machine of the above character which embodies 40 a skidding frame and a box drag positioned within and pivotally secured to the said skidding frame.

Another object of the present invention is the provision of new and novel means for 45 raising and lowering the box drag and for holding the same in its raised or inoperative position when so desired.

Another object of the present invention is to provide such an improved leveling machine of the above character wherein the box drag associated therewith is provided with 50 a rake, a cutting harrow and a plane board arranged one behind the other in the order named.

A further object of the present invention 55 is to provide such an improved leveling machine which while simple in its construction is nevertheless strong, sturdy and durable, practical and efficient in its operation, easy and cheap to manufacture and well designed 60 for the purposes for which it is intended.

With these and numerous other objects in view, the invention resides in the novel construction, combination and formation of parts as will be more specifically hereinafter 65 described, illustrated in the accompanying drawings, and particularly pointed out in the appended claims.

In the drawings forming a part of the application and wherein like characters of reference denote corresponding parts throughout the several views:

Figure 1 is a side elevation of an improved land leveling machine constructed in accordance with the present invention.

Figure 2 is a top plan view thereof.

Figure 3 is a front end view of the same.

Figure 4 is a longitudinal central sectional view taken through the improved machine.

Figure 5 is a sectional view taken on line 5-5 of Figure 4.

Figure 6 is a sectional view taken on line 6-6 of Figure 4.

Referring now more in detail to the accompanying drawings wherein for the purpose of illustration has been disclosed one practical embodiment of the present improved land leveling machine, the letter A generally indicates the skidding frame thereof and B the box drag arranged within and pivotally carried by the said skidding frame, as will be more fully hereinafter described.

The skidding frame A embodies in its construction, a pair of longitudinally extending spaced boards or skids 10 and 11, the opposite ends thereof being preferably undercut as indicated at 12 and 13 so that the frame may be readily drawn in either direction. The skids 10 and 11 are connected adjacent 100 their forward ends by means of the transverse beam 14 and adjacent their rear ends by means of a transverse beam 15, the forward beam 14 being rigidly secured in position by means of suitable braces 16 while the rear beam is firmly secured by means of the braces 17.

Secured to the inner surfaces of the skids

10 and 11 adjacent to but slightly in the rear of the forward transverse beam 14 are the vertically arranged supports 18 and 19 and secured to the upper ends of the said supports and extending therebetween is the transverse bar 20 carrying intermediate its ends an eye 21. The opposite ends of the said transverse bar 20 project beyond the said supports 18 and 19 and have secured thereto the upper ends of the brace bars 22 and 23, the lower ends of which are secured to the outer surfaces of the skids 10 and 11. The transverse bar 20 may be further braced by means of suitable straps 24.

15 Carried by the skids 10 and 11 intermediate the ends thereof is a bench generally indicated by the numeral 25 and consisting of the spaced front and rear uprights 26 and 27 secured to the outer surfaces of the skids and supporting at their upper ends the seat 28 extending transversely of and between the said skids, the said rear uprights 27 extending upwardly beyond the seat 28 and having secured there-

25 to the transversely extending back rest 29. The box drag B embodies in its construction the longitudinally extending side boards 30 and 31 which are arranged inwardly of the skids 10 and 11 and have their rear ends pivotally mounted upon the bolts 32 and 33. It will be noted that the side boards 30 and 31 of the box drag B are arranged approximately intermediate the ends of the skids 10 and 11 and that the said side boards extend upwardly beyond the upper edges of the said skids. The forward edges of the side boards 30 and 31 of the box drag are beveled at an angle of approximately 45° as indicated at 34 and 35 and extending between the said side boards 30 and 31 and secured to the bevelled forward edges 34 and 35 thereof is a rake 36 provided with a plurality of teeth 37. The rake teeth 37 are preferably disposed on a line with the bottom edges of the skids and are set permanently at an angle of 45° to gather weeds or other rubbish that might otherwise interfere with the successful working of the machine.

30 Secured to the inner surfaces of the side boards 30 and 31 of the box drag approximately about two feet in the rear of the rake 36 are the oppositely disposed strips 38 and 39, said strips being arranged at an angle of approximately 45°. Extending between the said strips 38 and 39 and secured thereto is a cutting harrow generally indicated by the numeral 40 and including a plurality of spaced harrow teeth 41 permanently set at an angle of approximately 45°, the points of the said teeth being preferably set about two-thirds of an inch below the level of the box drag B for the purpose of loosening the surface of the ground as the machine travels thereover.

35 Secured to the inner surfaces of the side

boards 30 and 31 approximately about two feet in the rear of the strips 38 and 39 are the oppositely disposed strips 42 and 43, said strips also being preferably arranged at an angle of approximately 45° and having 70 secured thereto the transversely extending planing board 44 which may be either of wood or metal the lower edge of the said board being preferably on a level with the lower edge of the box drag and with the 75 skids 10 and 11, said planing board being tilted permanently at an angle of 45°. When the dirt loosened by the harrow teeth 41 comes to the planing board 44, this dirt is carried or pushed along and left in all of 80 the low places automatically and all dirt in excess of what the board can carry passes over the top thereof and is then engaged and carried along by a second planing board 45 which is similarly arranged about two 85 feet in the rear of the planing board 44, and secured to the strips 46 and 47 carried by the inner surfaces of the side boards 30 and 31. Suitable braces 48, 49 and 50 may also be provided for securing the opposite 90 ends of the said planing boards 44 and 45 in proper rigid positions and it will be appreciated that any desired number of planing boards may be employed.

95 Carried by the drag box drag B adjacent the forward end thereof is a bench 51 which simply consists of the spaced front and rear uprights 52 and 53 secured to the side boards 31 and 30 and supporting at their upper ends a customary seat 54.

100 The numerals 55 and 56 indicate a pair of looped straps which are pivotally secured as at 57 and 58 to the outer surfaces of the side boards 30 and 31 of the box drag B intermediate the ends thereof and above the skids 10 and 11. Received within the said looped straps 55 and 56 are the forward ends of the longitudinally extending beams 59 and 60, said beams extending rearwardly of the machine between the uprights 26 and 27 of the bench 25 and beneath the seat 28 thereof, said beams having their outer ends connected by the transverse hand gripping bar 61. The beams 59 and 60 are adapted to rest upon blocks 62, one of each of which is secured to the inner surfaces of the uprights 26 and 27 of the bench 25.

115 For the purpose of limiting the downward movement of the forward end of the box drag B, there is secured to the outer surface of each of said side boards 30 and 31, a block 63, said blocks engaging the upper edges of the said skids 10 and 11 whereby to limit the downward movement of the said box drag B.

120 Secured to the skids 10 and 11 immediately adjacent the forward ends thereof are chains 64 and 65 while also secured to the said skids rearwardly of the chains 64 and 65 are a second pair of chains 66 and 67,

the forward ends of all of the said chains 64, 65, 66 and 67 being connected to a boss ring 68.

The chains 64 and 65 should be as short as possible in order not to afford any play when turning the machine around while the chains 66 and 67 should be just long enough to do all of the pulling when the team drawing the machine is going straight ahead. There is also secured to the boss ring 68 a hook 69 and a chain 70 carrying at its outer end a hook 71. In practice, a double tree or spreader is adapted to be fastened to the hook 69 for table leveling when there is no turning around in order to lighten the draft. However, in roughing or in the preliminary leveling of a field before the tables are formed, the double tree or spreader is secured to the hook 71. When the hook 71 is not being used, it may be engaged with the eye 21 carried by the transverse bar 20.

The rear end of the machine is also provided with a pair of short chains 72 and 73 and a pair of somewhat longer chains 74 and 75, the forward ends of all of which chains are connected to a boss ring 76. These chains serve the same purposes as the forward chains when the machine is being drawn rearwardly.

In the use of the present machine and when it is desired to rough a newly cleared tract of land, the box drag B is lowered so that the blocks 63 engage the upper surfaces of the skids 10 and 11 and a team of horses or tractor is then hooked onto the end of the hook 71. The machine is then ready for work and when roughing a newly cleared tract, it is simply customary to draw or pull the machine in any desired direction wherever there may be a high place which it is necessary to shave down. Owing to the fact that the weight of the beams 59 and 60 and hand gripping bar 61 almost counteract the weight of the front bench 51, the machine is so balanced that the box drag B will be automatically raised to release any dirt and especially clods that it cannot dispose of on the first trip. During this operation, the driver should sit on the rear bench 25 so as not to interfere with this automatic feature of the machine but in the event that an extra strong team or a tractor is being used, the driver can sit on the front bench 51 to hold the nose of the box drag down.

On the other hand, let us suppose that it is desired to level an irrigating table and as set forth hereinabove, in table leveling, it is not important whether there be much or little or in fact any difference between the level of one table and that of any other but it is very important to have just a little difference in level between both ends of the table so that the land will slope down from the irrigating ditch.

Also, the surface must not only be a perfect plane without hollows or humps but the dirt for leveling must all come from the higher end of the table and be smeared down along towards the lower end thereof. For this reason, the present machine cannot work both going and coming for fear of bringing back on the return trip that dirt which has just been carried down on the prior trip. Likewise, if the machine should be turned around, it might be very apt to make ridges that would mar the table.

Therefore, it is advisable to start at the higher end of the table close to one edge thereof and go straight down the table. When doing this, the double tree or spreader is attached to the hook 69 and in order to bring the machine back after the downward trip, it is simply necessary to unhook the double tree from the hook 69, turn the team around and hook the double tree or spreader to the boss ring 76 at the rear end of the machine. The machine can then be pulled back empty without the necessity of turning it around and on doing so, the tilting lever should be held downwardly and in any desired manner in order to hold the nose of the box drag upwardly so that the machine will run on the skids 10 and 11. This is also done when moving the machine to or from work.

As the machine is being drawn downwardly towards the lower end of the table, the rake teeth 37 which extend level with the bottom of the box drag simply serve to remove weeds or other relatively large obstructions from the path of the machine while the harrow teeth 31 are adapted to loosen the ground and the planing boards 44 and 45 then carry this loosened dirt and spread the same, thereby filling up all hollow places and making the table perfectly plane.

Also, as the machine is being drawn downwardly the operator should press upon the hand bar 61 so as to gradually raise the forward end of the box drag in order that the work may be uniform. Should the operator raise the box drag not gradually but suddenly, the box would release all of the surface dirt in one heap and leave a border or ridge across the table some distance from the lower end or foot thereof. Therefore, the operator should start tilting the box drag when he reaches a certain distance from the foot of the table.

From the foregoing, it is believed that the construction and operation of the present invention will be readily appreciated and it is to be understood that while there has been disclosed one practical embodiment of the present invention, which, in practice, will give efficient and reliable results, that changes in the details of construction thereof may be resorted to without departing from or sacrificing the spirit of the invention.

so long as such changes fall within the scope of the appended claims.

What is claimed is:

1. In a machine of the character described, a main frame including a pair of longitudinally extending skids, a second frame including a pair of side boards positioned between the said skids and extending longitudinally thereof, means for pivotally connecting the rear ends of the said boards to said skids, a handle extending rearwardly and upwardly and having its forward end connected with said boards for raising and lowering the forward ends thereof, blocks carried by said boards and engaging said skids for limiting the downward movement of said boards, a rake carried by and extending between said boards and having a plurality of teeth terminating on a level with the bottom edges thereof, a harrow secured to and between said boards in the rear of said rake and having a plurality of teeth projecting below the bottom edges of said boards, and a planing board secured to and between said boards in the rear of said harrow and having its lower edge even with the bottom edges of said boards.
2. In a machine of the character described a main frame including a pair of longitudinally extending skids, a second frame including a pair of longitudinally extending side boards having their rear ends pivotally connected with said skids, a handle secured to said boards for raising and lowering the forward ends thereof, blocks carried by said boards and engaging said skids for limiting the downward movement of the former, a rake carried by said boards and having a plurality of teeth projecting forwardly therefrom and on a level with the lower edges thereof at an angle of approximately forty-five degrees, a harrow carried by said side boards in the rear of said rake and positioned to extend slightly below the lower edges thereof at an angle of approximately forty-five degrees, and a planing board carried by said side boards in the rear of said harrow and positioned at an angle of approximately forty-five degrees, the lower edge of said planing board being even with the bottom edges of the said side boards.
3. In a machine of the character described, a main frame structure comprising a pair of longitudinally extending skid members, a second frame arranged within said first mentioned frame between said members, means for connecting said second frame with the first mentioned frame to permit vertical swinging movement of one end of said second frame, a rake element having the teeth thereof arranged in a forwardly and downwardly directed manner, carried at the forward part of said second frame, and further having said teeth positioned with their ends substantially in the same plane as the lower edges of said skids, a harrow structure arranged rearwardly of said rake in a forwardly and downwardly directed manner and extending below the lower edges of said skids, and a planing board arranged rearwardly of said harrow and within said second frame, and having the lower edge thereof directed forwardly and downwardly and terminating in a plane substantially parallel with the lower edge of said skid, and means for swinging said second frame substantially as and for the purpose described.

4. In a machine of the character described, a main frame structure comprising a pair of longitudinally extending skid members, a second frame arranged within said first mentioned frame, between said members, means for connecting said second frame with the first mentioned frame to permit vertical swinging movement of one end of said second frame, a rake element having the teeth thereof arranged in a forwardly and downwardly directed manner, carried at the forward part of said second frame, and further having said teeth positioned with their ends substantially in the same plane as the lower edges of said skids, a harrow structure arranged rearwardly of said rake in a forwardly and downwardly directed manner, and extending below the lower edges of said skids, and a planing board arranged rearwardly of said harrow and within said second frame, and having the lower edge thereof directed forwardly and downwardly and terminating in a plane substantially parallel with the lower edge of said skid, and means for swinging said second frame substantially as and for the purpose described, the degree of inclination of said rake teeth, harrow and planing board being substantially the same.

In testimony whereof I affix my signature.

JULES L. HENRY.
